his Atty.

UNITED STATES PATENT OFFICE.

PAUL J. ALWART, OF CHICAGO, ILLINOIS.

PORTABLE APPARATUS FOR ELEVATING AND SCREENING COAL AND OTHER UNSCREENED MATERIAL.

Application filed July 25, 1921. Serial No. 487,397.

To all whom it may concern:

Be it known that I, PAUL J. ALWART, a citizen of the United States, and a resident of Chicago, Cook County, and State of Illinois, have invented certain new and useful Improvements in Portable Apparatus for Elevating and Screening Coal and Other Unscreened Material, of which the following is declared to be a full, clear, and exact description.

This invention relates to portable apparatus for elevating and screening coal and other unscreened material, and its principal object is to provide an elevating and screening apparatus which may be readily moved about from one position to another and arranged to elevate unscreened material from one level to another, remove the fine material and deliver the screened material into wagons, car, bags or other receptacles.

As is well known, there is considerable dust and fine material intermingled with coal, both anthracite and bituminous coal, and frequently large quantities of coal are stored in coal yards which must be screened before it can be marketed and sold at any reasonable price, and in accordance with the common and well known methods of screening coal taken from a coal pile, a great deal of labor and time is consumed in preparing it for the market, thereby greatly increasing the cost of the screened coal. One of the objects of the present invention is to reduce the time and labor necessary for cleaning coal and consequently reduce the cost of preparing the coal for the market. Another object is to simplify the operation and reduce the time and labor ordinarily consumed in cleaning the coal, delivering it in cleaned condition into wagons, cars, bags or other receptacles.

With these and other objects and advantages in view, this invention consists in the several novel features hereinafter fully set forth.

The invention is clearly illustrated in the accompanying drawings, in which:

Fig. 1 is a side elevation of an apparatus embodying a simple form of the present invention; Fig. 2 is an end elevation of the screening mechanism thereof, looking in the direction of the arrow 2 in Fig. 1; Fig. 3

is a detail, vertical, longitudinal section, partly broken away, through the screen portion of the apparatus and Fig. 4 is a detail plan of a fragment of the elevator mechanism.

Referring to said drawings, the reference character 5 designates an elevator of common and well known construction, employing an endless conveyer 6 having the usual flights 7 that travel in a trough 8 and act to convey material from the bottom to the top of the elevator. Located over the endless conveyer, at the bottom of the elevator, is a hopper 9 into which the material is shoveled or dumped as the case may be. An electric motor 10 is mounted in the elevator 5 and it drives the endless conveyer 6 by suitable gearing 11 and chain drive mechanism, the chain 12 of which is trained over a sprocket wheel 13 mounted at the upper end of the elevator, on a shaft 14, which carries sprocket wheels over which the endless conveyer 6 is trained. The elevator 5 is supported in an inclined position by a frame 15 which is mounted on supporting wheels 16, whereby it may be readily moved about from place to place. The lower end of the elevator rests upon the ground and its upper end is located above the screening mechanism of the apparatus in position to discharge the elevated material into the hopper of the screening mechanism.

The screen mechanism comprises a tower 17 preferably made of upright frame members 18 and horizontal connecting bars 19, riveted or otherwise rigidly secured together to provide a rigid skeleton like tower structure. Rollers or caster wheels 20 secured to the bottom of the tower, provide means whereby it may be readily moved from place to place. At the upper end of the tower is a hopper 21 preferably having two inclined hopper bottoms 22 upon which the material is discharged from the elevator 5. At and below the lower end of the hopper bottoms 22, is an inclined screen 23 of suitable mesh, to permit of the escape of the finer material, and said screen is provided on its lower side with cam shoes 24 that rest on cam blocks 25 mounted on a cam shaft 26 which is journaled in bearings 27 mounted on the frame members 28 of the tower. The upper end of the inclined screen 23 may be

supported by the tower in any suitable and convenient manner. The cam shoes act to violently knock the screen in an upward direction and a bumping bar, preferably a cushioned bumping bar 44, is provided below the lower end of the screen to relieve the structure from some of the shock. Pivotally supported on frame members 29 are retarding gates 30, the lower ends of which rest 10 on the screen and retard the flow of material along the same. Said gates also act to arrest the flow of material when the screen is at rest. The screen may be provided with a tensioning device and the bumping bar 15 may be constructed in accordance with the corresponding parts shown and described in my application for patent on screening apparatus filed February 18, 1921, Serial No. 445,980, to which reference is made for a 20 fuller description. On one end of the shaft 26 is a sprocket wheel 31 which is connected to a sprocket wheel 32 on the shaft 14 of the elevator 5 by the sprocket chain 33. Whenever the electric motor of the elevator is set 25 in motion and the shaft 14 of the endless conveyer is thereby caused to move, the cam shaft 26 is consequently rotated through the instrumentality of the sprocket wheels 32, 31, and sprocket chain 33, and any coal or other 30 material discharged into the hopper 21 is acted upon the screen 23, but as soon as the motor is stopped, the conveyer ceases to run and the cam blocks cease to agitate the screen, whereupon the flow of the coal down 35 the screen is immediately arrested by the gates 30.

The motor 10 is controlled from the tower by a control switch 34, preferably of the remote control type, which is supported by the 40 tower and is connected to the motor by conductor cords 35. Other conductor cords 36 run from said switch to the main line. A switch actuating hand lever 37, fulcrumed upon the tower, is connected to the switch 34 by a link 38, and a spring 39 connects said hand lever 37 with the tower and acts to raise it and thereby raise the link 38 and open the switch mechanism of the switch 34, whenever the lever is released. The 50 switch is closed by depressing the hand lever 37.

Below the screen 23 is a chute 40 having an inclined bottom 41 which receives the finer material separated from the coal or other 55 material by the screen, and said chute 40 delivers said finer material to one side of the tower. An inclined coal chute 42 projects from the lower end of the inclined screen 23 and delivers the screened coal at a place 60 considerably above the level of the place from which the unscreened coal was taken. The lower end of said coal chute 42 is contracted somewhat in order that a coal bag may be placed thereunder to receive the 65 screened coal and a counterweighted swing-

ing gate 43 is provided in said coal chute, near its discharge end, to positively arrest the flow of any coal passing beyond the retarding gates 30 when the swinging gate is lowered.

In the operation of the apparatus, the elevator is moved to a position close to a coal pile or other material which is to be screened, and the screening mechanism is moved under the upper end of the elevator 75 in position to receive coal or other material discharged from its upper end and the sprocket wheels 31, 32, are then connected by the sprocket chain 33. To deliver clean, screened coal into a wagon or into bags contained in the wagon, the latter is driven underneath the coal chute 42, coal is shoveled into the hopper 9, and the lever 37 is depressed, thereby setting in motion the motor. If coal is to be bagged, a bag is 80 placed under the discharge end of the coal chute 42 and the hand lever 37 then depressed to close the switch and held in depressed condition until the bag is practically filled, whereupon the lever is raised 85 to open the switch and break the circuit to the motor. As soon as the endless conveyor stops the screen ceases to discharge any more coal.

With the use of a screen agitated by the 95 cams as described, a large capacity is obtained for given size and consequently the coal can be run through the apparatus and delivered in clean, screened condition in 100 much less time than if the coal were screened in accordance with the common and well-known methods and placed in the wagon or other receptacle.

By providing the hand lever in position accessible to the attendant on the wagon, he 105 can control the operation of the elevator and screen, and can fill bags in the wagon, with clean, screened coal, taken from a pile of unscreened coal. This saves all of the time usually required to first bring the coal 110 to the coal bins and run it through the usual screens.

It is quite possible to use the screening apparatus separate from the elevator, in cases 115 where it is desired to screen coal or other material taken from a railway car or the like, in which case the cam shaft is connected to a motor and the coal is shoveled into the hopper 21 from the car. In this way the unscreened coal may be delivered in 120 clean condition directly from the car into a wagon or bags, thereby saving considerable time in preparing the coal for the market. While the apparatus has been described in connection with the screening of coal, it is 125 quite obvious that it may be used for screening other material such as stone, sand, etc.

More or less variation of the exact details of construction is possible without departing from the spirit of this invention; 130

I desire, therefore, not to limit myself to the exact form of the construction shown and described, but intend, in the following claims, to point out all of the invention disclosed herein.

I claim as new and desire to secure by Letters Patent:

1. A portable elevating, screening and loading apparatus comprising, in combination, a portable elevator mounted on wheels and having an electric motor operated conveyer, a portable tower, an inclined shaking screen mounted in said tower, a hopper carried by said tower between the upper ends of said conveyer mechanism and screen, screen agitating means driven from the motor of said elevator, and an electric control switch for said motor mounted on said tower and having a switch actuating handle accessible adjacent the discharge end of the screen, whereby an attendant adjacent said screen may control the simultaneous operation of the conveyer and screen, said elevator and tower being separately movable, whereby the distance between the receiving end of the ele-

vator and the discharge end of the screen may be varied.

2. A portable elevating, screening and loading apparatus comprising, in combination, a portable elevator mounted on wheels and having electric motor operated conveyer mechanism, a portable tower, an inclined shaking screen mounted in said tower, a hopper carried by said tower between the upper ends of said conveyer mechanism and screen, material retarding and arresting means above said screen, screen agitating means driven from a member of said conveyer mechanism and an electric control switch for the motor of said conveyer mechanism, having a switch actuating handle located adjacent said screen, whereby an attendant adjacent the discharge end of said screen may control the simultaneous operation of said conveyer and screen, said elevator and tower being separately movable, whereby the distance between the receiving end of the elevator and the discharge end of the screen may be varied.

PAUL J. ALWART
